UNITED STATES PATENT OFFICE.

HARRY C. HANSON, OF ST. PAUL, MINNESOTA.

COAT.

Application filed February 24, 1925. Serial No. 11,031.

To all whom it may concern:

Be it known that I, HARRY C. HANSON, a citizen of the United States, residing in St. Paul, in the county of Ramsey and State of Minnesota, have invented a new and useful Coat, of which the following is a specification.

My invention relates to improvements in coats.

- 10 An object of the invention is to provide an improved lined-to-the-edge coat wherein that portion of the lining extending to the one front edge of the coat shell constitutes a flap and the adjacent portion of said shell 15 comprises a pocket to receive the flap, said flap, when unsheathed from said pocket, providing a fly between which and said pocketed portion of the coat the opposing front edge of said coat may be inserted.
- 20 With the foregoing and other objects in view, which will appear in the following description, the invention resides in the novel combination and arrangement of parts and in the details of construction herein- 25 after described and claimed.

In the drawings, Fig. 1 is an elevational view of a coat embodying my invention, the lining flap being shown as sheathed in its pocket in the coat shell; Fig. 2 is a fragmentary view illustrating the flap unsheathed from said pocket; Fig. 3 is a sectional view taken on the line 3—3 of Fig. 1; Fig. 4 is a similar detail view taken on the line 4—4 of Fig. 2; Fig. 5 is a detail sectional view showing the edges of the coat overlapped and the flap within its pocket and Fig. 6 is a detail sectional view similar to Fig. 5, but showing the flap unsheathed from its pocket and in position functioning 40 as a body protecting fly.

Referring to the drawings, it will be seen that the illustrated garment includes the usual double breasted shell 10 having the ordinary complementary buttons 11 and loops 12 to fasten the coat closed. This type of coat, customarily sheep-lined, is used largely for rough winter wear by persons engaged in active pursuits. Some coats of this nature are lined only to within four 50 inches or so of the edges of the front portions of the coat, the lapping unlined portions serving as the sole protection for the front of a wearer's body. Other coats are lined to one edge and thus constructed provide a complete body encircling lining when the coat is closed. My improved coat is of

the general nature of the last mentioned type of garment.

Instead, however, of permanently affixing the entire sheep lining to the coat shell, I 60 limit the permanent part of my lining to a main portion 13, both edges of which fall short of the edges of the front portions 10^a, 10^b of the shell 10. Extending from one edge of the main lining portion 13 in the 65 form of a continuation thereof is a flap 14 of sheep-lining, the same being bound with a hinge-strip 15, which is secured by a seam 16 to the coat shell portion 10^a. This flap 14 is normally sheathed in an inwardly 70 opening pocket (Fig. 1) provided at the inner margin of the front portion 10^a of the coat shell with which said flap 14 is associated. Said pocket is formed between the coat shell portion 10^a and a combined 75 facing and pocket-piece 17, the inner edge of which is left free in the stitching of said piece 17 to the coat shell. The hinge-strip 15, previously mentioned, is fastened to the coat shell by the seam 16 along a line adjacent to the mouth of the flap pocket and the flap 15 may be sheathed therein (Figs. 1 and 3) or unsheathed therefrom (Figs. 1 and 3), as may be desired. Snap fastener members 18, secured at intervals along the 80 hinge strip 15, have complementary fastener members 18^a on the free edge of the pocket piece 17. The fastener members 18, 18^a provide for locking the pocket-piece 17 closed upon the flap 14 sheathed within the 85 pocket. Thus disposed, the flap 14 serves its purpose in completing the encircling of the body by the shell lining while the pocket piece 17, covering said flap, faces the full lined portion 10^a of the coat shell and 90 finishes said coat portion to correspond with the other permanently finished front portion thereof.

A user normally wears the coat with the flap 14 sheathed as above explained, but in 100 cold windy weather, he may wish to employ the flap 14 as a body protecting fly. This latter use of the flap 14 is had by first unsnapping the fastener members 18, 18^a then unsheathing said flap 14 from its pocket 105 and, finally, buttoning the coat closed with the edge of the front portion 10^b inserted between the pocketed portion 10^a and the flap 14 (Fig. 6). In its relation as a body protecting fly, the flap 14 not only traps the 110 elements against entry to the wearer's body, but functions, as in its alternate relation, as

a completing element in the body encircling lining of the coat.

Changes in the specific form of my invention, as herein disclosed, may be made 5 within the scope of what is claimed without departing from the spirit of my invention.

Having described my invention, what I claim as new and desire to protect by Letters Patent is:

- 10 1. In a coat, a shell, a pocket piece extending along the inner margin of one front portion of said shell and secured thereto at one edge thereof to form an inwardly opening pocket between said pocket piece and front shell portion, a lining for said shell including a main lining portion and a flap comprising a continuation of said lining portion, a hinge-strip carrying said flap portion and secured to the shell along a line adjacent to the mouth of said pocket, said flap being adapted to be sheathed in said pocket or unsheathed therefrom and, in said latter relation, to provide a body protecting fly in that position of the other portion of said shell disposed between said flap and said pocketed shell portion, a fastener member on the free edge of said pocket piece and a complementary fastening member on said hinge strip, said members in cooperation, one with the other, being adapted to secure the pocket closed upon the flap sheathed therein.
- 15 2. In a coat, a shell, a pocket piece extending along the inner margin of one front portion of said shell and secured thereto at one edge thereof to form an inwardly opening pocket between said pocket piece and front shell portion, a lining for said shell including a main lining portion and a flap comprising a continuation of said lining portion, a hinge-strip carrying said flap portion and secured to the shell along a line adjacent to the mouth of said pocket, said flap being adapted to be sheathed in said pocket or unsheathed therefrom and, in said latter relation, to provide a body protecting fly in that position of the other portion of said shell disposed between said flap and said pocketed shell portion, a fastener member on the free edge of said pocket piece and a complementary fastening member on said hinge strip, said members in cooperation, one with the other, being adapted to secure the pocket closed upon the flap sheathed therein.
- 20 3. In a coat, a shell, a pocket piece extending along the inner margin of one front portion of said shell and secured thereto at one edge thereof to form an inwardly opening pocket between said pocket piece and front shell portion, a lining for said shell including a main lining portion and a flap comprising a continuation of said main lining portion at one edge thereof, a hinge-strip carrying said flap portion and secured to the shell along a line adjacent to the mouth of said pocket, said flap being adapted to be sheathed in said pocket or unsheathed therefrom and, in said latter relation, to provide a body protecting fly in that position of the other portion of said shell disposed between said flap and said pocketed shell portion, a fastener member on the free edge of said pocket piece and a complementary fastening member on said hinge strip, said members in cooperation, one with the other, being adapted to secure the pocket closed upon the flap sheathed therein.
- 25 4. In a coat, a shell having an inwardly opening pocket located at the inner margin of one front portion thereof and a lining for said shell including a flap portion hinged to the shell along a line adjacent to the mouth of said pocket, said flap being capable of being sheathed in said pocket or unsheathed therefrom, the latter relation of said flap adapting the same for use as a body protecting fly between which and the adjacent pocketed portion of said shell the opposing front shell portion may be inserted.
- 30 5. In a coat, a shell, a pocket piece extending along the inner margin of one front portion of said shell and secured thereto at one edge thereof to form an inwardly opening pocket between said pocket piece and front shell portion, a lining for said shell including a main lining portion and a flap comprising a continuation of said lining portion, a hinge-strip carrying said flap portion and secured to the shell along a line adjacent to the mouth of said pocket, said flap being adapted to be sheathed in said pocket or unsheathed therefrom and, in said latter relation, to provide a body protecting fly in that position of the other portion of said shell disposed between said flap and said pocketed shell portion, a fastener member on the free edge of said pocket piece and a complementary fastening member on said hinge strip, said members in cooperation, one with the other, being adapted to secure the pocket closed upon the flap sheathed therein.
- 35 6. In a coat, a shell, a pocket piece extending along the inner margin of one front portion of said shell and secured thereto at one edge thereof to form an inwardly opening pocket between said pocket piece and front shell portion, a lining for said shell including a main lining portion and a flap comprising a continuation of said lining portion, a hinge-strip carrying said flap portion and secured to the shell along a line adjacent to the mouth of said pocket, said flap being adapted to be sheathed in said pocket or unsheathed therefrom and, in said latter relation, to provide a body protecting fly in that position of the other portion of said shell disposed between said flap and said pocketed shell portion, a fastener member on the free edge of said pocket piece and a complementary fastening member on said hinge strip, said members in cooperation, one with the other, being adapted to secure the pocket closed upon the flap sheathed therein.
- 40 7. In a coat, a shell, a pocket piece extending along the inner margin of one front portion of said shell and secured thereto at one edge thereof to form an inwardly opening pocket between said pocket piece and front shell portion, a lining for said shell including a main lining portion and a flap comprising a continuation of said lining portion, a hinge-strip carrying said flap portion and secured to the shell along a line adjacent to the mouth of said pocket, said flap being adapted to be sheathed in said pocket or unsheathed therefrom and, in said latter relation, to provide a body protecting fly in that position of the other portion of said shell disposed between said flap and said pocketed shell portion, a fastener member on the free edge of said pocket piece and a complementary fastening member on said hinge strip, said members in cooperation, one with the other, being adapted to secure the pocket closed upon the flap sheathed therein.

being adapted to be sheathed in said pocket or unsheathed therefrom and, in said latter relation, to provide a body protecting fly in that position of the other portion of said shell disposed between said flap and said pocketed shell portion, and means for fastening the free edge of the pocket piece to close the pocket upon the flap sheathed therein.

3. In a coat, a shell, a pocket piece extended along the inner margin of one front portion of said shell and seamed thereto at the edge thereof to form an inwardly opening pocket between said pocket piece and front shell portion, a lining for said shell including a main lining portion and a flap comprising a continuation of said main lining portion at one edge thereof, a hinge-strip carrying said flap portion and secured to the shell along a line adjacent to the mouth of said pocket, said flap being adapted to be sheathed in said pocket or unsheathed therefrom and, in said latter relation, to provide a body protecting fly in that position of the other portion of the shell is inserted between said pocketed shell portion and said flap.

4. In a coat, a shell having an inwardly opening pocket located at the inner margin of one front portion thereof and a lining for said shell including a flap portion hinged to the shell along a line adjacent to the mouth of said pocket, said flap being capable of being sheathed in said pocket or unsheathed therefrom, the latter relation of said flap adapting the same for use as a body protecting fly between which and the adjacent pocketed portion of said shell the opposing front shell portion may be inserted.

In testimony whereof I have signed my name to this specification.

HARRY C. HANSON.
